UNITED STATES PATENT OFFICE.

HENRY F. ZARTH, OF SHAKOPEE, MINNESOTA, ASSIGNOR TO AMERICAN RANGE CORPORATION, OF SHAKOPEE, MINNESOTA.

DESIGN FOR A RANGE.

Application filed February 12, 1927. Serial No. 20,720. Term of patent 7 years.

To all whom it may concern:

Be it known that I, HENRY F. ZARTH, a citizen of the United States, residing at Shakopee, in the county of Scott and State of Minnesota, have invented a new, original, and ornamental Design for Range, of which the following is a specification, reference being had to the accompanying drawings, forming part thereof, wherein—

Fig. 1 shows a perspective view of the article showing my new design; and
Fig. 2 shows a plan view of the same.

What I claim is:—

The ornamental design for a range, as shown.

HENRY F. ZARTH.
